UNITED STATES PATENT OFFICE.

ELROY C. ROBERTSON, OF CLEVELAND, OHIO, ASSIGNOR TO THE FRANTZ PREMIER COMPANY, OF EAST CLEVELAND, OHIO, A CORPORATION OF OHIO.

DESIGN FOR A SUCTION-CLEANER CASING.

52,809.

Specification for Design.

Patented Dec. 24, 1918.

Application filed May 31, 1917. Serial No. 172,107. Term of patent 14 years.

To all whom it may concern:

Be it known that I, ELROY C. ROBERTSON, a citizen of the Dominion of Canada, and a subject of the King of Great Britain, residing at Cleveland, in the county of Cuyahoga and State of Ohio, have invented a new, original, and ornamental Design for a Suction-Cleaner Casing, of which the following is a specification, reference being had to the

accompanying drawing, forming part hereof, wherein—

Figure 1 represents a perspective view, and Fig. 2 a right hand elevation of a suction cleaner casing embodying my invention.

What I claim is:

The ornamental design for a suction cleaner casing, as shown.

ELROY C. ROBERTSON.
